Primary Examiner — Sandra S Snapp*Assistant Examiner* — Ieisha N Price(74) *Attorney, Agent, or Firm* — Sheridan Ross P.C.(57) **CLAIM**

The ornamental design for notebook pocket, as shown and described.

DESCRIPTION

FIG. 1 is a perspective view of the notebook pocket shown on a notebook with elements thereof and the notebook shown in phantom;

FIG. 2 is a front view thereof;

FIG. 3 is a top view thereof;

FIG. 4 is a bottom view thereof; and,

FIG. 5 is a left side view thereof, the right side view is a

mirror image thereof.

The broken lines shown are included for illustrative purposes only form no part of the claimed design.

1 Claim, 3 Drawing Sheets(56)
